DESIGN FOR A PROJECTING LANTERN

Charles F. Dutton, Rocky River, Ohio

Application November 29, 1941, Serial No. 104,394

Term of patent 14 years

To all whom it may concern:

Be it known that I, Charles F. Dutton, a citizen of the United States of America, residing at Rocky River, in the county of Cuyahoga and State of Ohio, have invented a new, original, and ornamental Design for a Projecting Lantern, of which the following is a specification, reference being had to the accompanying drawing, forming part thereof.

In the drawing,

Fig. 1 is a side perspective view of a projecting lantern, showing my new design, the opposite side presenting substantially the same appearance as the side shown;

Fig. 2 is a rear elevational view thereof; and
Fig. 3 is a front elevational view of the same.

I claim:

The ornamental design for a projecting lantern, substantially as shown and described.

CHARLES F. DUTTON.
